JOHN FAULDER BURN, OF LONDON, AND JOHN STUART LANCASTER, OF WARWICK, ENGLAND.

ROTARY MIXING MACHINE.

Application filed March 24, 1927, Serial No. 178,060, and in Great Britain September 28, 1926.

This invention relates to rotary mixing machines, and more particularly to machines for mixing concrete or similar material.

It is common to employ a receptacle, known as a drum, for this purpose the sides of which taper frusto-conically to a mouth of smaller diameter, the bottom resembling a basin with curved surfaces having a central portion adapted to form a bearing for supporting it rotatably upon an axle, inclined so as to cause the material contained therein to fall back repeatedly on to the curved bottom, and the drum being tilttable in order to discharge its contents when desired. The chief aim in apparatus of this kind is to ensure that every particle of aggregate receives a coating of cement, without which the concrete cannot be said to be properly mixed. In order to improve the mixing effect, it has heretofore been proposed to provide the drum with vanes, ribs or projections, but none of these prior proposals, so far as known, has yet resulted in a sufficiently efficient mixing.

It is, therefore, an object of the invention to provide a new and improved mixing drum that shall mix together the ingredients which form the concrete or the like more efficiently than heretobefore in a reasonably short time and by a smooth motion which avoids jarring and strain upon the machine. A further object or aim is to provide apparatus that shall be simple in construction, economical in cost, and inexpensive to run. The above objects and aims are well demonstrated in our invention, a brief description of which will now be given, with the aid of the accompanying drawings, illustrating a mixing receptacle made according to a preferred form of the invention.

Figure 1 is a vertical section.

Figure 2 is a perspective view of the same with the upper part removed for the purpose of showing the interior of the lower portion.

Figure 3 is an external perspective view taken from a position towards the rear or bottom of the receptacle.

Figure 4 is an elevation of the interior looking straight into the receptacle, the upper part being removed for the same purpose as in Figure 2.

The reference letters which are repeated in the different figures denote the same parts.

The mixing receptacle, for convenience called a drum, is of the known type con-

sisting of a short cylinder A with a frusto-conical end B, presenting an opening C of reduced diameter, and closed at the other end by a basin-like base D, which meets the cylindrical part in a curve. Rising from the centre of the basin-like base D is a boss E forming the bearing for the pivot pin F on which the drum is adapted to be rotated by means of the usual outside circular rack G which is provided upon all drums of this class. The axis of such a drum is inclined at an upward angle of twenty to thirty degrees to the horizontal or more or less, that is, so that the material which is being mixed therein shall not escape until the drum is tilted for discharging the contents in the usual manner. According to the specific embodiment of the present invention that is herein illustrated and described, the base D of the drum is formed with an inclined track, and with a step connecting the high and low ends of the track, or portions of the track, together.

The central boss E above mentioned stands up somewhat like a tapered cone, truncated or flat on the top where the centre pin F is terminated by an exposed round head H, the other end of the boss merging in a curve with the base D, avoiding a sharp angle at the junction. To understand the invention, one may now imagine the interior of the base D to be bisected by a plane passing through the axis, dividing the base, therefore, on a diametral line. A sudden step or depression J is provided—by suitably shaping the base—along each of the two radial lines (where this diametrical division occurs) on either side of the central boss E, and the surface of the base D rises in an inclined path K from the depression at one radial line until the opposite radial line is reached where another similar drop or step J occurs. Expressed differently, the surface of the interior of the base is divided into two semi-circular tracks or half-circuits K K, each half K resembling the half of one coil of a helix made of flat ribbon which ribbon may however be curved or otherwise shaped in cross sectional view if desired. The upward terminal edge of each track K is broader than the lower end or root, as the latter necessarily lies in the restricted depth of the base D which gradually widens upwardly to its maximum diameter at the cylindrical portion A of the drum. Such

details of design, however, may not be material. It is essential to provide the steps or sudden depressions J such as above mentioned for the following reason. The ingredients get carried for only a small distance against gravity upon each inclined track K as the drum rotates counter-clockwise (as viewed in Fig. 4), the material continuously rolling and falling over the surfaces of the tracks K K. It is necessary that the material shall not travel upwards to any height. The early falling is the most important result to aim at, whereby the material describes a practically continuous movement, as one incline immediately follows the other, with a step in between. The inclination of each track K becomes steeper in relation to the vertical as it travels higher, and overhangs somewhat when it is at the highest point, as seen in the section K, Fig. 1. This prevents the material from rising into the drum any distance, and so entirely overcomes separation of the large and small particles. The material is continuously turned over, the action closely resembling a kneading motion in which gravity is the chief factor.

The centre boss E acts as a divider or deflector when the charge is so increased as to cause the volume of the wave to reach this height in the drum. In some cases, one track could be used instead of two and in such a case only one step J would be required. A pair of helical or equivalent deflectors L (one only shown—Fig. 1) is provided, these being set in an opposite direction higher up in the drum to compel the material, when a large batch is treated, to fall back again into the heart of the mix and become agitated over again.

The interior formation above described is shown on the drawings as if made by pressing the metal of the base D into the desired shape, visible also from the outside, as seen clearly in Fig. 3. If preferred, the number of steps or depressions J can be increased beyond the two specified. Also they can be made otherwise than by pressing, if desired, as will be easily understood.

We claim:

1. In a mixing machine, a rotary mixing receptacle or drum having a frusto-conical termination presenting at one end an opening of reduced diameter and closed at the other end by a basin-like base, the latter having a boss at its centre forming a bearing on which the drum may rotate, the interior of the base essentially being in the form of an inclined track and with a step to connect the high and low ends of the same for the purpose specified.

2. In a mixing machine, a drum as claimed in claim 1 of which the base is formed by the operation of pressing or stamping.

3. In a mixing machine, a rotary mixing

drum having a base and an open top and walls connecting the base with the top, means for rotating the drum about an axis disposed longitudinally of the drum, the drum being provided with a track disposed between the axis and the walls and having one or more portions that extend substantially spirally about the axis, whereby one of the ends of the track is disposed nearer the open top than is the other end, the track having a portion connecting the ends together to form a step.

4. In a mixing machine, a rotary mixing drum having a base and an open top and walls connecting the base with the top, means for rotating the drum about an axis disposed longitudinally of the drum, the drum being provided with a track disposed between the axis and the walls and having a plurality of portions each extending substantially spirally about the axis, whereby one of the ends of each portion is disposed nearer the open top than is its other end, the track having a portion connecting the said one end of one portion to the said other end of another portion to form a step.

5. In a mixing machine, a rotary mixing drum having a base and an open top and walls connecting the base with the top, means for rotating the drum about an axis disposed longitudinally of the drum, the drum being provided with a track disposed between the axis and the walls and having one or more portions that extend substantially spirally about the axis, whereby one of the ends of the track is disposed nearer the open top than is the other end, the track having a portion connecting the ends together to form a step, and the track being connected throughout to the walls.

6. In a mixing machine, a rotary mixing drum having a base and an open top and walls connecting the base with the top, the base having a bearing projecting interiorly into the drum longitudinally of the drum, a pin being adapted to extend into the bearing, means for rotating the drum about the pin, the walls tapering toward the axis of rotation in the neighborhood of the open top, whereby the cross dimension of the open top is less than the cross dimension of other parts of the drum, the drum being provided with a track disposed between the bearing and the walls and having one or more portions that extend substantially spirally about the bearing, whereby one of the ends of the track is disposed nearer the open top than is the other end, the track having a portion connecting the ends along the walls and the bearing to form a longitudinally extending step, and the track being connected throughout to the walls and the bearing.

7. In a mixing machine, a rotary mixing drum having a basin-shaped base and a frusto-conical open top and walls connecting the

base with the larger diameter of the frusto-conical top whereby the opening at the top is of reduced diameter, the base having a centrally disposed bearing projecting in-

teriorly into the drum longitudinally of the drum, a pin being adapted to extend into the bearing, means for rotating the drum about the pin, the base being interiorly shaped to constitute a track extending substantially spirally about the bearing between the bearing and the walls, whereby one end of the track is disposed nearer the open top than is the other end, the track having a portion connecting the ends to form a longitudinally extending step.

8. In a mixing machine, a rotary mixing drum having a basin-shaped base and a frusto-conical open top and walls connecting the base with the larger diameter of the frusto-conical top, whereby the opening at the top is of reduced diameter, the base having a centrally disposed bearing projecting interiorly into the drum longitudinally of the drum, a pin being adapted to extend into the bearing, means for rotating the drum about the pin, the base being interiorly shaped to constitute a track having a plurality of portions each extending substantially spirally about the bearing between the bearing and the walls, whereby one of the ends of each portion is disposed nearer the open top than is its other end, the track having portions connecting the said one end of

each portion with the said other end of each adjacent portion to form longitudinally extending steps between the portions.

9. In a mixing machine, a drum having a body portion and a frusto conical upper portion the walls of which taper from the body portion towards the top of the drum, the drum being open at the top only, whereby the opening at the top is of reduced diameter, the body portion having a bearing member projecting interiorly into the drum longitudinally of the drum, the drum being adapted to be positioned with the bearing member at an incline to the horizontal and being constructed and arranged to be rotated about the inclined bearing member, and the drum being provided with a track extending around the bearing member and having one or more portions inclined with respect to the bearing member and connected together at their extremities by one or more steps.

10. In a mixing machine, a drum as claimed in claim 9 in which the one or more inclined portions of the track and the one or more steps together extend continuously completely around the bearing.

11. In a mixing machine, a drum as claimed in claim 1 in which the surface of the track is curved in cross section.

In witness whereof we have signed this specification.

J. FAULDER BURN.
JOHN LANCASTER.
